UNITED STATES PATENT OFFICE.

GEORGE FREDERIC MOORS, OF OWENSBORO, KENTUCKY.

ROTARY ENGINE.

1,121,653.

Specification of Letters Patent. Patented Dec. 22, 1914.

Application filed March 16, 1914. Serial No. 824,986.

To all whom it may concern:

Be it known that I, GEORGE F. MOORS, a citizen of the United States of America, a resident of Owensboro, in the county of Daviess and State of Kentucky, have invented certain new and useful Improvements in Rotary Engines, of which the following is a full, clear, and exact description, reference being had to the accompanying drawings, forming a part of this specification.

My invention relates to a rotary engine and in some respects the present invention is an improvement on the rotary engine shown in U. S. Letters Patent No. 1,029,941, issued to me June 18, 1912.

One of the objects of the present invention is to provide a rotary engine having its rotating elements balanced so that the rotor may be driven at a very high rate of speed without materially vibrating the engine structure.

The engine shown in the prior patent referred to includes eccentrics movable about the axis of the drive shaft and rings adapted to oscillate on said eccentrics so that the moving elements are not well balanced and therefore not adapted to be run at a high speed.

In accordance with my present invention the eccentrics are fixed and the rings rotate about the center of the eccentric members. The stator includes the eccentrics and a support therefor, while the rotor includes the rings which rotate continuously about the center of the eccentrics and an annular rotor member which rotates continuously about the axis of the drive shaft. The main distinction between the parts just referred to and the corresponding parts of my prior structure is to be found in the new rings and the new annular rotor member, each of said parts being balanced with respect to its axis of rotation. The rotating eccentric members of the prior structure are not balanced with respect to the axis of rotation and the rings of the old structure oscillate about a constantly changing axis of oscillation instead of rotating continuously about a fixed axis.

Another important feature of the present invention lies in certain engine elements, adapted to be operated by the expansion of fluid confined in a cylinder; combined with a turbine structure forming part of said engine elements and adapted to be impelled by the fluid discharged from the expansion cyl-

inder. To briefly explain the merits of this feature of my invention I will say that it is now a very common practice to operate turbine engines by means of steam exhausted from reciprocating engines or other engines which derive their power from the expansion of the steam. It has been considered an economical practice to construct two complete engines, one of which is operated by the expansion of the steam while the other is driven by the steam exhausted from the first engine. By my improvement the advantages of the two separate and distinct engines are obtained by merely locating turbine vanes on the rotor of a rotary engine, placing a casing around said turbine vanes and conducting the steam from the exhaust port of the rotary engine to the turbine vanes. In other words instead of constructing a complete engine separate and distinct from the rotary engine I merely provide the turbine vanes, the outer casing and a steam pipe for conducting steam to the turbine vanes.

Figure I is a longitudinal section of my rotary engine. Fig. II is a detail view of the inlet valve. Fig. III is a vertical section of the engine. Fig. IV is a transverse section taken approximately on the line IV—Fig. III, showing the inlet ports. Fig. V is a fragmentary view of one of the rotor heads, showing the inlet ports formed therein.

In the accompanying drawings: A designates a base provided with a casing member 1 and bearing members 2, 3 and 4. The base is surmounted by a casing member 5 and bearing members 6 and 7.

8 designates a fixed supporting rod secured to the bearing member 2 by a key 9, Fig. I, said rod constituting a support for eccentrics 10. The eccentrics are preferably mounted on a square portion of the fixed rod 8 and filler blocks or wedges 11 are arranged between the eccentrics and said rod. The fixed eccentrics form part of a stator around which the rotor elements revolve.

The rotor comprises rings 12 rotatably mounted on the eccentrics, an annular rotor member 13 surrounding said rings, heads 14 and 15 secured to the ends of the annular rotor member, and a power shaft 16 secured to the head 14. Ball bearings 17 are arranged between the eccentrics 10 and the rings 12, and similar bearings 18 are arranged between the fixed rod 8 and the

stator heads 14 and 15. The power shaft 16 extends through the bearing 3 and is supported near its outer end by a ball bearing 19 in the bearing member 4. The fixed rod 8 is preferably provided with oil ducts 20 and 21 through which oil is delivered to the ball bearings 18.

The engine I have shown is a double structure including two of the fixed eccentrics 10 and two of the rotatable rings 12, each of said rings being closely fitted to the side walls of an expansion chamber 22 or 23. These expansion chambers are formed by the annular rotor member 13, its heads 14 and 15, and a partition wall 24 which divides the rotor into two compartments.

The rotor includes abutment arms 25 connecting the annular rotor member 13 to the rings 12. Each abutment arm 25 is pivotally connected at 26 to the annular rotor member and pivotally connected at 27 to one of the rings 12. The abutment arms are provided with heads 28 extending into the expansion chambers 22 and shanks 29 arranged in exhaust chambers 30.

The abutment heads 28 as well as the rings 12 are closely fitted to the walls of the expansion chambers 22, and steam is introduced into said expansion chambers through ports 31, see Figs. III and IV. The annular rotor member 13 is arranged eccentrically with relation to the axis of the rings 12 and said rings contact with the annular rotor member 13 as shown in Fig. III. These parts 19 and 13 are closely fitted together at the point of contact to prevent leakage of the steam. It will now be understood that steam, or other fluid under pressure, entering the expansion chamber through a port 31, is confined between the left side of the abutment head 28 (Fig. III) and the ring 12 and the annular rotor member 13. The pressure is of course exerted in all directions and the following description taken in connection with Fig. III will show that such pressure will impart a rotary movement to all of the rotor elements. The inner face of the annular rotor member 13 is provided with a V shaped notch forming a wall 33 against which the steam impinges. The steam in the expansion chamber presses downwardly upon the left portion of the ring 12, however the eccentric 10, forming part of the stator, constitutes a support for said ring and it therefore cannot move downwardly at the left side of Fig. III. The steam also impinges against the abutment head 28 and the wall 33 in the annular rotor member, and since these rotor elements are free to revolve the rotor moves in the direction indicated by the arrows. The annular rotor member 13 turns about the axis of the supporting rod 8 which is alined with the drive shaft 16; and the ring 12 turns about the axis of the eccentric member 10.

The ring member 12 is arranged eccentrically with relation to the annular rotor member 13 but each of said members turns around a fixed axis and the point of contact between said members remains at the left side of the ring 12 as shown at 35 Fig. III. The steam is finally exhausted from the expansion chamber through an exhaust port 36 in the inner face of the annular rotor member, the exhaust taking place when the port 36 passes beyond the contact point 35. The exhaust ports 36 lead to the exhaust chambers 30 which communicate with each other through a port 37, and the rotor head 14 is provided with an exhaust passageway 38 leading from an exhaust chamber 30 to a passageway 39 in the drive shaft 16. The bearing 3 is provided with an annular passageway 40 surrounding the end of the exhaust passageway 39, and at this point the shaft is preferably surrounded by a perforated sleeve 41.

42 designates a series of pipe sections leading from the annular passageway 40 to a discharge nozzle 43 at the upper portion of the casing member 5. The annular rotor member 13 is provided, at its periphery, with a series of turbine vanes 44 closely fitted to the outer casing and the steam passing through the nozzle 43 is discharged onto said vanes and finally passes out through an exhaust pipe 46.

The live steam is primarily introduced into my engine through an inlet passageway 47 formed in the outer end of the fixed supporting rod 8, see Fig. I. The head 15 of the rotor is provided with inlet ports 48 and 49 leading from the annular rotor member 13 to an inlet chamber 50 which surrounds the supporting rod 8. An inlet valve 51 secured to the rod 8 and arranged in the inlet chamber 50 is adapted to open and close the inlet passageways 48 and 49. The inlet valve 51 is preferably in the form of a collar fixed to the supporting rod 8, said valve being cut away as shown in Figs. I and II. Steam entering the structure through the primary inlet passageway 47 (Fig. I) passes through a port 52 and flows into the inlet chamber 50. As the rotor revolves, its passageways 48 and 49 are opened and closed by the stationary valve 51 in the inlet chamber, and steam is thus admitted to the expansion chambers 22 and 23. The passageway 48 leads to a transverse passageway 52 which communicates with the inlet port 31 opening into the expansion chamber 22, see Figs. III and IV. The passageway 49 (Fig. IV) leads to a transverse passageway 53 extending entirely across the annular rotor member 13 and communicating with a bypass 54 which leads to the inlet port 31 of the expansion chamber 23. The various ports and passageway just described are only for the purpose of conducting steam

from the inlet chamber 50 to the inlet ports 31 in the expansion chambers 22 and 23 and it will be understood that the invention is not in any way limited to the arrangement 5 of the passageways I have described.

I claim:

1. A rotary engine comprising a stator, a rotor surrounding said stator, said parts being provided with inlet and exhaust ports 10 through which fluid under pressure may be conducted to drive the rotor, the rotor being provided with turbine vanes, a casing around said turbine vanes, and means for conducting fluid from said exhaust port to 15 said turbine vanes.

2. A rotary engine comprising a stator, a rotor surrounding said stator, said rotor forming an expansion chamber in which a fluid under pressure may be expanded to 20 drive the rotor, said parts being provided with inlet and exhaust ports through which the fluid is conducted, the rotor being provided with turbine vanes, a casing surrounding 25 said turbine vanes, and means for conducting fluid from said exhaust port to said turbine vanes for the purpose described.

3. A rotary engine comprising, a stator including a support and an eccentric fixed to said support, and a rotor including a ring 30 rotatably mounted on said eccentric, an annular rotor member surrounding and contacting with the periphery of said ring, said annular rotor member being concentric to said support and eccentric with respect to 35 the axis of said ring, and a pivotally mounted abutment arm connecting said annular rotor member to said ring.

4. A rotary engine comprising a stator including a support and an eccentric fixed 40 to said support, and a rotor including a ring rotatably mounted on said eccentric, an annular rotor member surrounding and con-

tacting with the periphery of said ring, said annular rotor member being arranged eccentrically with relation to the axis of said 45 ring, and a pivotally mounted abutment member connecting said annular rotor member to said ring.

5. A rotary engine comprising a stator including a support and an eccentric fixed 50 to said support, and a rotor including a ring rotatably mounted on said eccentric, an annular rotor member surrounding and contacting with the periphery of said ring, said annular rotor member being arranged eccentrically with relation to the axis of said 55 ring, and a pivotally mounted abutment member connecting said annular rotor member to said ring, the said annular rotor member being provided with inlet and exhaust ports arranged on opposite sides of said abutment member.

6. A rotary engine comprising a casing, bearings, a support aligned with said bearings, an eccentric on said support and an inlet valve on said support, all of the aforesaid parts being fixed, combined with a ring rotatably mounted on said eccentric, a rotor member surrounding and contacting with said ring, said rotor being arranged concentrically with relation to said ring, a pivotally supported abutment member connecting said ring to said rotor member, the rotor member being provided with turbine vanes which are fitted to said casing, and said rotor member being provided with an inlet port leading from said valve to the interior 70 of the rotor member, and means for conducting fluid from the interior of said rotor member to said turbine vanes.

GEORGE FREDERIC MOORS.

In the presence of—

IRENE HAYDEN,

A. F. TABB.
